UNSATURATED KETONES

William J. Farrissey, Jr., Northford, Conn., assignor, by
mesne assignments, to ESSO Research and Engineering
Company, Elizabeth, N.J., a corporation of Delaware
No Drawing. Filed Dec. 16, 1963, Ser. No. 330,617
3 Claims. (Cl. 260—586)

The present invention is directed to new and useful materials produced from the products obtained from the selective air oxidation of cyclooctadiene. More particularly, the invention is concerned with the unsaturated ketones derived from cyclooctadiene. In its more specific aspects, the present invention is directed to the arrangement of 3-keto-1,5-cyclooctadiene to bicyclo(4,2,0)oct-2-en-4-one.

The present invention may be briefly described as the ketones which may be produced from the products obtained by the selective air oxidation of cyclooctadiene. It has been found that the oxidation of cyclooctadiene with molecular oxygen at a temperature within the range from about 50 to about 75° C. produces an oxidation product from which may be separated a mixture of 3-hydroperoxy-1,5-cyclooctadiene and 6-hydroperoxy-1,4-cyclooctadiene. These hydroperoxides, 3-hydroperoxy-1,5-cyclooctadiene and 6-hydroperoxy-1,4-cyclooctadiene, represent the starting materials of the present invention.

It is preferred that the hydroperoxides obtained in the oxidation of cyclooctadiene be converted to the corresponding ketones by treating the hydroperoxides with a mixture of an acid chloride and a nitrogen base. The process is preferably carried out at a temperature within the range of —10 to +10° C. but is kept as cool as possible to prevent a tarry product from forming. Acid chlorides, such as propionyl, benzoyl chlorides and the like, may be employed but acetyl chloride is preferred. The preferred nitrogen base is pyridine, but other nitrogen bases, such as lutidine, collidine, and picoline, may be used. The conversion of the hydroperoxides to the corresponding ketones produces a mixture of 3-keto-1,5-cyclooctadiene and 6-keto-1,4-cyclooctadiene. The ketone mixture was analyzed, and it was apparent from the NMR spectrum that these two ketonic materials were present.

According to another aspect of the present invention, the ketone mixture consisting of 3-keto-1,5-cyclooctadiene, and 6-keto-1,4-cyclooctadiene is heated to a temperature within the range of about 175 to about 200° C. During the heating of the mixture, the 3-keto-1,5-cyclooctadiene is rearranged to the bicyclo(4,2,0)oct-2-en-4-one. The analysis of the ketone mixture after being heated shows a marked change in the infrared and NMR spectrum. Again, the analysis shows two unsaturated ketones which are present in the same relative amounts as the two isomeric ketones obtained in the conversion of the hydroperoxides.

According to the present invention, unsaturated ketones which are valuable intermediate chemicals are obtained. As will be pointed out hereinafter, the unsaturated ketones may be precursors for nylon 8 or for the production of cis-(2-carboxycyclobutyl) acetic acid.

The present invention is further illustrated by the following examples which are set forth to merely illustrate and not to limit the present invention.

Example 1

In a 1-liter flask equipped with condenser, high speed stirrer, oxygen inlet tube and thermal well is placed 200 cc. (176.6 g., 1.63 moles) of cis,cis-1,5-cyclooctadiene and 0.4 g. of azoisobutyronitrile. The solution is heated to 60° C. with a constant temperature bath, and pure oxygen gas is admitted to the system. Oxidation is continued until 4.23 liter (0.19 mole, 11.7%), of oxygen has been ab-

2

sorbed. Unreacted olefin is removed by vacuum evaporation at 40° C. after which there remains 25.52 g. of a thick viscous oil. The oil is separated into a hydroperoxide phase and a peroxide phase by treatment with a petroleum ether-benzene mixture. On addition of 204 cc. of petroleum ether and 41 cc. of benzene and cooling to —5° C. two layers are formed. The upper layer is decanted and solvent evaporated from it to yield 12.37 g. (0.088 mole, 4.6%) of hydroperoxide analyzed as 3-hydroperoxy-1,5-cyclooctadiene and 6-hydroperoxy-1,4-cyclooctadiene.

Example 2

A solution of 21.66 g. of a crude mixture of cyclooctadiene hydroperoxides obtained by the air oxidation of cyclooctadiene and consisting of 3-hydroperoxy-1,5-cyclooctadiene and 6-hydroperoxy-1,4-cyclooctadiene in 115 ml. of chloroform is cooled to 0° C. Sixty ml. of pyridine is added rapidly to this solution, and thereafter, 8.4 ml. of acetyl chloride in 10 ml. of chloroform is added slowly to the solution over 2.5 hours. The solution is further stirred for 45 minutes at 0° C. and then allowed to warm to room temperature while stirring for another 2.25 hours. The product is poured in a separatory funnel, and the product is washed free of pyridine with 1 N HCl. The residual acid is washed free with water, and the product is dried in a solvent evaporator. A crude product (18.17 g.) is obtained which upon distillation yielded 9.6 ml. of ketones boiling at 61—66° C. at 1.9 mm. The ketone product is a mixture of the following two compounds:

Example 3

A portion of the ketone product formed in accordance with Example 2 plus a crystal of hydroquinone is heated under nitrogen for 6.5 hours at a temperature between 175 to about 200° C. Upon distillation, there is obtained material having a boiling point of between 61.5—69.5° C. at 0.9 mm. This material was analyzed by infrared and NMR spectrum and exhibited peaks on the NMR spectrum at 3.2 τ , a doublet at 4.0 τ while the remaining hydrogen residues were centered at 7.0 and 7.9 τ . The material analyzed was found to have the following structure:

Example 4

A sample of the bicyclic ketone produced in the rearrangement of Example 3 in methanol solution is treated with ozone at —35° C. After evaporation of the solvent, the ozonide, 0.3 g., is oxidized with 5 ml. of 30% hydrogen peroxide in 25 ml. of 90% formic acid. The solution is heated slowly at reflux for one hour. On evaporation of the solvent, a peroxide-free product is obtained. The product is separated into a toluene insoluble solid fraction and a white solid having a melting point of 105—111° C. after two recrystallizations from toluene. The white solid was proved to be cis-(2-carboxycyclobutyl) acetic acid having the following structural formula:

Example 5

A portion of the materials produced in accordance with Example 2 is treated by passing hydrogen through the mixture, the mixture being in the presence of platinum at

room temperature. The product obtained is essentially pure cyclooctanone which may be further treated in a known manner for use in the production of nylon 8.

The nature and objects of the present invention having been completely described and illustrated and the best mode thereof set forth, what I wish to claim as new and useful and secure by Letters Patent is:

What is claimed is:

1. The compound, 6-keto-1,4-cyclooctadiene.
2. The compound having the formula:

3. The method of rearranging 2,6-cyclooctadienone to

bicyclo(4,2,0)oct-2-en-4-one which comprises heating 2,6-cyclooctadienone in the presence of hydroquinone to a temperature of between about 175 to about 200° C.
